CENTRIFUGAL PUMP

Giles Philip Eliot Howard and Alexander Ivanoff,
Luton, EnglandApplication August 2, 1946, Serial No. 687,823
In Great Britain July 11, 1945Section 1, Public Law 690, August 8, 1946
Patent expires July 11, 1965

2 Claims. (Cl. 103—103)

1

This invention relates to centrifugal pumps, and more particularly to centrifugal pumps which are intended to handle liquid at high temperatures.

The object of the invention is the provision of improvements in such pumps, the purpose of which is, either to reduce the temperature at certain points of the pump, such as the stuffing box, or to limit the maximum rate of change of temperature at such points as the joint faces of the pump casing which may be caused by the sudden variation of the temperature of the pumped fluid. In a centrifugal pump the liquids are customarily moving at high velocities, with the result that the walls and the internal parts are traversed by rapidly moving fluids. Any sudden changes in the temperature of the fluid are therefore communicated without great delay to the surface of the metal comprising such walls or internal parts, and such sudden changes result in violent thermal stresses.

In accordance with the present invention a series of heat baffles is provided, the purpose of which is to create between the baffles and the walls or between several baffles a single layer or multiple layers of stagnant liquid. The heat transfer through such layers would be largely by conduction and natural convection and would therefore be considerably reduced in magnitude as compared with the forced convection which would result were the baffles not present.

The invention may be suitably applied to the pumps of pump-motor combinations, as described and claimed in the co-pending application of Alexander Ivanoff, Serial No. 792,013, filed Dec. 16, 1947, in which the pump pumps fluid at high temperature and pressure and the motor casing, which is in effect a part or extension of the pump casing, contains fluid whose pressure is of the same order as the pressure of the fluid being pumped.

In order that the invention may be the more clearly understood a centrifugal pump structure in accordance therewith will now be described, reference being made to the accompanying drawing which is a sectional side elevation of said pump structure.

Referring to this drawing, the pump structure therein illustrated is associated in one assembly with a driving electric motor, in the same general way as in the co-pending application Serial No. 792,013 aforesaid. In the present drawing the whole of the motor is omitted save for the near end of the motor casing which is designated by the reference 1. The pump impeller is desig-

2

nated by the reference 2. As in said co-pending application the motor casing 1 and the pump casing 3 are embodied in one common casing, which has a reduced neck 4 between said motor and pump casings, in which neck is located one of the journal bearings for a shaft 5 which is common to both pump and motor.

Also, as in said co-pending application, the fluid within the common casing is cooled by circulating it, from the upper end of the motor casing (not shown), through a coil immersed in a cooling tank (not shown), and back to the common casing through a hole in the wall of the reduced neck 4 by way of a pipe 6.

15 The impeller 2 is mounted on the lower extremity of the shaft 5 and is adapted to draw the fluid in coaxially through an inlet port 7 at the lower end of the pump casing, and deliver it radially through an outlet port 8 in the plane of 20 said impeller. Between said impeller and said outlet port 8 is provided a diffuser 9. This is the subject of our co-pending application Serial No. 687,824, filed of even date herewith, now matured into Patent No. 2,450,143 of Sept. 28, 1948 25 and will not be further described herein.

In accordance with the present construction the back cavity 10 of the pump casing 3, i. e. the cavity on the side of the pump impeller 2 remote from the inlet conduit 7, is made cylindrical and 30 larger, both as to its diameter and its axial extent, than that shown in our co-pending application aforesaid. Also the journal bearing for the shaft 5 is set back further from the pump impeller 2 so as to be clear of the said back cavity 35 10. In this cylindrical back cavity 10 are located a plurality of disc-shaped baffles 11 coaxially round the shaft 5.

The said back cavity 10 is in communication, in the usual way, by way of holes 12 through the 40 pump impeller, with the pump input, and is therefore filled with fluid, and, in the ordinary way, the temperature of this fluid owing to forced convection, would rapidly approximate, throughout said back cavity, that of the fluid being 45 pumped, and thus, if for example the fluid being pumped were to rise to a high temperature, the fluid in the back cavity would rapidly transfer the same temperature to, for example, the journal bearing.

50 When baffles 11 as above described are employed, however, a plurality of layers of substantially stagnant liquid are produced between the several baffles, and between the end baffle and the end of the back cavity, and the rate of heat 55 transfer through these several layers, which can

only be by conduction and natural convection, will be much less than that caused by the forced convection if the baffles were not present. Thus the journal, for example, will remain at a considerably lower temperature.

The baffles 11 may be mounted, at their inner edges, on a fixed sleeve 13 closely surrounding the shaft 5 and at their outer edges they may be touching the inner periphery of said back cavity. The sleeve 13 at its end remote from the pump may be formed with a flange 14 whereby it is attached to the back wall of the pump casing. For giving increased rigidity to the baffles 11 a number of posts 15 are provided which are mounted at their upper ends to the back wall of the pump casing and which extend downwardly through holes in said baffles, suitable spacing washers being mounted on said posts 15 between said baffles.

As the metal of the baffles 11 does not, in any case, offer great resistance to the passage of heat it is intended that said baffles should be made of comparatively thin gauge metal and that the sleeve 13 carrying them should only be strong enough to resist the forces due to impact of the moving liquid. It will be seen that, provided it is ensured that the layers of liquid are substantially stagnant as stated, there is no need to ensure a hermetic seal between the baffles and the adjacent parts.

In the particular example of the invention above described the main purpose of the baffles 11 is to ensure that should the aforescribed cooling circulation, by way of the cold coil and the pipe 6, fail, owing for example to stoppage of the motor through a failure of the electric current there would be no violent flow of heat, from the body of the liquid inside the pump casing, or from the metal comprising the pump shell, towards the electric motor.

As shown, the pump casing 3 consists of two portions 3a and 3b having annular junction faces at 16 in a plane transverse to the shaft 5. It is a further specific purpose of this particular example of the invention to limit the maximum rate of change of temperature at the region of these junction faces. The said cylindrical back cavity 10 in which the baffles 11 are located is constituted by a cylindrical recess in the back or upper portion 3a of the pump casing 3, that is the portion which carries the stuffing box. The outer surface 17 of this portion 3a is also made cylindrical over most of the length of said back cavity. The front or lower portion 3b of the pump casing, in which the inlet and outlet are formed, has a rear annular extension 18 which surrounds the said outer cylindrical surface 17 of the portion 3a, and the surface at the rear end of this extension 18 abuts against the front surface of an annular enlargement or flange 19 formed on said portion 3a, and the two portions are bolted together by means of bolts 20 at these two abutting surfaces, which thus constitute the said junction faces of the pump casing. Owing to the baffles 11 the rate of heat flow from inside the back cavity to the junction face on the portion 3a of the casing is much restricted. The rate of heat flow to the junction face on the portion 3b of the casing, which depends on conductivity through the substantial thickness of the aforesaid rear extension 18, is also relatively low. The heat flow to the region of the junction is therefore fairly slow and the temperature of the junction faces rises and falls slowly, thus giving the junction faces a chance to attain the same temperature, by radiation and conduction from one side of the junc-

tion to the other. The arrangement has the additional desirable feature that the reduction of the rate of change of temperature of the junction also minimises the difference of temperature between the aforesaid flanges 19 on the portion 3a of the casing and the bolts 20 passing through said flange. These bolts 20, being surrounded by a thin layer of air, which it is almost impossible to avoid, are generally slower in responding to temperature changes because they have to receive their heat either axially from that part which is screwed into the metal or by radiation and convection across the air layer. Either of these processes is somewhat slow. If the temperature of the flange 19 drops rapidly, the temperature of the bolts 20 drops considerably more slowly, with the result that the bolts become longer in relation to the thickness of the flange, and this reduces the clamping pressure holding the junction tight. The present construction, in reducing the rate of change of heat at the region of the junction faces, increases the tendency of the bolts 20 to be at the same temperature as the two parts of metal which they bolt together, and therefore enables the junction to remain tight and unchanged throughout.

Further constructional details are in the main sufficiently clear from the drawing. It will be seen that the shaft 5 for some distance from its lower end is made hollow, the impeller 2 being mounted on a plug element which is, say, welded in the open lower end of said shaft. By making the shaft hollow in this way the rate of heat transfer from the pump towards the motor is still further reduced.

It will also be seen that the external surface of the reduced neck 4 is formed with annular vanes 21. This increases the surface radiation of heat from said neck portion and still further reduces the transfer of heat from the pump towards the motor.

In the particular construction being described, a tilting-pad type of bearing is employed for the shaft 5. The reference 22 designates the tilting pads. The bearing surfaces of these pads engage around a sleeve 23 which is fast on the shaft 5 and they make tilting engagement with a surrounding sleeve member 24 which forms a lining within the reduced neck 4. As in prior British Patent No. 553,443 the member 24 has a conical inner surface with which the pads 22 engage, and a cage element 25 screwed into said member 24 draws the pads against said conical surface.

As will be clear from the drawing the member 24 has an end flange whereby it is secured to the back wall of the pump casing by the same bolts which secure the sleeve 13.

We claim:

1. A centrifugal pump comprising a pump impeller, a pump shaft on which said pump impeller is mounted, said pump shaft extending rearwardly from said pump impeller, a pump casing for said pump impeller having a fluid inlet and outlet, said pump casing being provided with a back cavity at the rear of said pump impeller, through which back cavity said shaft passes in contact with the fluid in said back cavity, said back cavity being in free communication with the fluid inlet aforesaid, means for reducing the rate of heat flow through said back cavity, comprising a plurality of spaced stationary baffles located in said back cavity in planes transverse to the axis of said shaft, each of said baffles having a hole through it, through which said shaft passes with a relatively small clear-

ance between said shaft and said baffles, and stationary means surrounding said shaft and sealing the spaces between said baffles at the region of the edges of their holes, said stationary means defining a fluid cut-off between said baffles and said shaft, and preventing the generation of motion in the fluid between said baffles by the rotation of said shaft.

2. A centrifugal pump as defined in claim 1, wherein said baffles at their outer edges substantially touch the inner periphery of said back cavity.
